FOLDING RACK FOR BEDS

Jeannette E. Pesola, Bolton Road, South Lancaster, Mass.
Filed Dec. 29, 1959, Ser. No. 862,679
1 Claim. (Cl. 5—318)

This invention relates to a new and improved folding rack which is adapted particularly to be applied to a bed for the purpose of holding the bed-clothing or other articles at the foot or side of the bed, in out-of-the-way position, while the bed is occupied or for the purpose of holding the bed-clothing while the bed is being made up, etc.

It is one of the principal objects of the present invention to provide such a rack which is foldable in a manner to be completely hidden away under the bed, but which at the same time is easily extended out from under the bed to fold into upright vertical condition to accomplish the purposes aforesaid.

Another object of the invention resides in the provision of a foldable rack as above described which may be applied to a bed to the frame thereof, or to the bed slats, or to the parts of a box frame mattress support or the like, so that it is seen that the rack may be applied to the bed either by the house-holder or it may be applied to an inner spring box frame by the manufacturer and the unit sold with the rack attached.

The invention further relates to arrangements and combinations of parts which will be hereinafter described and more particularly set forth in the appended claim.

Reference is to be had to the accompanying drawings, in which:

FIG. 1 is a view in front elevation showing the foot of a bed with the rack attached thereto in folded condition;

FIG. 2 is a similar view showing the rack in partly extended and in fully extended conditions;

FIG. 3 is a side elevational view of the bed illustrating the bracket for holding the rack and showing the rack extended;

FIG. 4 is a similar view but showing the rack completely folded;

FIG. 5 is a detail view showing one form of latch for the rack to hold it extended;

FIG. 6 is a view in elevation, looking in the direction of arrows 6 in FIG. 5; and

FIG. 7 is a perspective view showing details of the folding rack structure.

In carrying out the present invention, the same has been illustrated as applied to the cross-pieces of a box spring and in the illustration herein, this rack could therefore be sold originally as a unit with the box spring or sold and attached separately. However, it is emphasized that the invention contemplates many other supports for the rack limited only by the fact that the rack must be secured to the bed in some way, whether to the spring frame for the mattress, to the bed frame itself, or in some other relationship. Also, it is to be understood that the folding rack should be completely concealed when it is folded under bed but that it is easily extended to an upright position preferably at the foot of the bed, but also at the side of the bed if desired, and it should be high enough to provide for adequate support of for instance the bedspread while the bed is occupied and also to hold other clothing, etc. as desired.

In any event, in the drawing an ordinary mattress is shown at 10 and an inner or box spring covered mattress support at 12. Holding the mattress support or box spring 12 from the floor, there may be provided Hollywood legs which can be secured to the box frame at the

2

under side thereof, or there may be utilized a frame such as a Harvard frame generally indicated at 14.

Secured underneath the bed in any desired position but as for instance to the cross-slats 16 (FIGS. 3 and 4) of the box spring 12, there are provided a pair of brackets generally indicated at 18, these brackets being spaced apart any distance desired for the width of the rack. As shown in FIG. 1, this spacing is adequate for a double bed and may also be used in a single bed, but in the single bed the rack is almost as wide as the bed itself.

The brackets 18 may take any form desired but in the present case it is preferred that they should be provided with elongated bearing elements for the sliding reception of sliding rods 20. These sliding rods are adequately held against flexure by means of the elongated bearings or brackets 18 as clearly shown in FIGS. 3 and 4, and they may be moved between the extreme conditions as shown in FIGS. 3 and 4.

If desired, the rods 20 may be secured together by some means at their rear ends in order to form a stop so that they will not be pulled completely out of the bearings. This stop may take the form of any kind of collar or a cross-rod 19, see FIG. 4. Also, these rods 25 if desired may be secured together at the forward portions of the brackets as indicated at 22. The member 22 is not needed in all cases but it serves as a stiffening means for the rack and also performs the function of a stop for the FIG. 4 position of the rack and as a handle.

In all cases it will be seen that brackets 18, rods 20, 22, etc. are placed well above the floor line regardless of whether brackets 18 are secured to the bed frame, or the mattress frame or box spring.

The forward end of each rod 20, or the corresponding ends of cross-rod 22, are provided with hinges or swivels for folding extension members which are generally indicated at 24. These members should be relatively strong and can be easily made of aluminum channels or the like. The lower end of members 24 are pivoted as at 26 and may take any form desired or the members 24 may be pivoted on hinges. In any event, members 24 comprise at least two parts joined together as by central hinges 28 and it is to be noted from FIG. 1 that when folded downwardly, these hinges 28 overlap each other. This is for the purpose of providing vertical length enough for the folding members 24 in order to cause the upper ends thereof to rise to a convenient position for the desired purpose of holding the bedclothes, etc.

The ends of folding members 24 are secured together by a cross-bar 30 which is preferably in the form of a tube or the like, and they are joined thereto as by hinges 32 or other pivot means. This member 24 forms the actual support for the bedclothes or other clothing, etc., which may be draped thereover when the rack is extended in the full-line position as shown in FIG. 2.

It has been found that ordinary hinges used at 28 and 32 and pivot 26 rigidify the folding rack to such an extent that no other rigidifying means is needed. However, some kind of latch should be utilized at the hinges 28 in order to keep these hinges in their extended condition as in full lines in FIG. 2. This latch can take any form as for instance pins, snaps, clips or a snap-button of the type shown in FIGS. 5 and 6 at 34, taking into an opening 36 in an extension 38 in one of the arms of the folding members 24 as is clearly shown therein. It is to be understood, however, that this is merely illustrative, and sliding or other latch means may be utilized.

When the rack is folded in the FIG. 1 position, it may be moved in under the foot of the bed as shown in FIG. 70 4, and the brackets 18 provide the sliding bearings for rods 20 to be spaced from the lower surface of the bed

to such an extent that the cross-rod 30 will move in under frame 14 without touching the same but in close association therewith. As seen in FIG. 4, the entire rack is completely concealed but the operator may merely bend down and grasp cross-rod 22 or other part of the rack, pull it forwardly to the FIG. 3 position, and then grasp the cross-rod 30 and bring the same up into its uppermost position, see the solid line showing of FIG. 2, whereupon the same is fully extended and ready for use. The entire device is just as easily re-folded by releasing the latches, folding members 24 and moving the same inwardly toward each other in their overlapped condition as shown in FIG. 1. Then the entire rack is moved inwardly under the bed in the FIG. 4 position.

Having thus described my invention and the advantages thereof, I do not wish to be limited to the details herein disclosed, otherwise than as set forth in the claim, but what I claim is:

A folding rack for attachment to a bed frame comprising a pair of brackets, means attaching the brackets to the bed under the frame depending therefrom, a rod slidable horizontally in each bracket, said rods being parallel, means connecting said rods, the means connecting said

5 rods comprising an extensible rack means, said extensible rack means including a pair of folding members hingedly associated with said rods at the corresponding ends thereof, a cross-top member securing said folding members together at the ends thereof opposite said rods, said cross-top member being hingedly associated with said folding extensible rack members, and means yieldably maintaining the latter in extended condition thereof, the motion of the rack being vertical and at right angles to the rods, and said brackets spacing the sliding rods from the underneath side of the bed a distance greater than the folded height of the rack so that the rack when folded down is slideable underneath the bed and does not interfere with the same when retracted to its folded position under the bed.
